UNITED STATES PATENT OFFICE

142,723

DESIGN FOR A BASEBALL GAME DEVICE

Maximilian C. Meyer, Brooklyn, N. Y.

Application December 13, 1944, Serial No. 116,884

Term of patent 14 years

(Cl. D34—5)

To all whom it may concern:

Be it known that I, Maximilian C. Meyer, a citizen of the United States, residing at Brooklyn, in the county of Kings and State of New York, have invented a new, original, and ornamental Design for a Baseball Game Device, of which the following is a specification, reference being had to the accompanying drawing forming part thereof.

I claim:

The ornamental design for a baseball game device, substantially as shown.

MAXIMILIAN C. MEYER.
